CLAIM

The ornamental design for a shredder ring in a food waste disposal unit, as shown.

DESCRIPTION

FIG. 1 is a front elevational view showing my new design of a shredder ring in a food waste disposal unit;
 FIG. 2 is a rear elevational view thereof;
 FIG. 3 is a top plan view thereof;
 FIG. 4 is a bottom plan view thereof;
 FIG. 5 is a left side elevational view thereof;
 FIG. 6 is a right side elevational view thereof;
 FIG. 7 is a perspective view from above thereof; and,
 FIG. 8 is a perspective view from below thereof.
